UNITED STATES PATENT OFFICE.

JACK SHERIDAN COWPER, OF SOUTH KENSINGTON, LONDON, ENGLAND.

BLOCK AND THE LIKE FOR ROAD PAVING AND OTHER PURPOSES.

Application filed December 29, 1922. Serial No. 609,703.

To all whom it may concern:

Be it known that I, JACK SHERIDAN COWPER, a subject of the King of Great Britain and Ireland, and residing at 24 Queensbury

5 Place, South Kensington, London, S. W. 7, England, have invented certain new and useful Improved Blocks and the like for Road Paving and Other Purposes, of which the following is a specification.

10 This invention relates to blocks, setts or the like for use principally in paving roads, and for other purposes.

The object of the invention is to provide improved means for forming a road surface capable of withstanding continuous traffic, in which rubber or any substance of pliable nature shall predominate, thereby practically eliminating noise, and rendering the traffic surface more durable than wood paving as it offers a greater resistance to wear and tear than the systems now in use.

15 It is well known that in ordinary wood or sett paving the lower surface of the sett bearing on the concrete base receives more 20 or less a continuous vibratory movement and depressing action, which is transmitted from the upper or traffic surface of the road by the vibration or movement set up by the traffic, the effect of which is to form depressions or "pot-holes" and render the traffic surface of the road uneven.

25 This is obviated by my invention according to which pure or waste rubber or a composite substance thereof or any substance of pliable nature is utilized preferably in block form to constitute for paving roads, a sett, brick or block of rectangular or other suitable shape or solid block having recessed, sunk or dished-out side surfaces in which 30 are located panels, insets, cores or the like of wood, cement, concrete, or other suitable material or substance, which form abutting surfaces when the blocks are placed in position in paving, the upper and lower surfaces being of rubber or pliant substance, thus forming a slightly yielding and noise-deadening surface for the traffic, and the lower surface bearing on the concrete or cement base, setting up a reaction to the 35 movement transmitted from the upper sur-

face by the traffic. The panels or the like constitute a reinforcing means to the surrounding rubber surfaces and prevent undue displacement of the latter, while permitting a quick and full return of the rubber portions to their normal positions as soon as the stressed condition of the rubber surfaces, caused by the traffic has been removed.

40 The blocks may be provided with increased rubber corners at the abutting sides by forming the ends of the panels with diagonally shaped corners.

45 At intermediate positions on the abutting surfaces niches or other devices are formed to allow for expansion and contraction, and interlocking holes and projections may be employed on the abutting surfaces for holding the blocks in position.

50 The proportions or sizes of the relative parts may be of any convenient kind for the purpose in view, and the invention provides a means of utilizing waste rubber, or rubber generally, whether pure or of a composite character.

55 The accompanying drawings illustrate embodiments in block or brick form, according to my invention.

In the drawings,

Figure 1 is a side elevation of block or brick having central cavity with tapered ends to receive a reinforcement.

Figure 2 is a transverse section through the centre of Figure 1.

Figure 3 is a transverse section of a plurality of blocks or bricks having a central web and combined with interlocking reinforcement.

Figure 4 is a side elevation of a plurality of blocks or bricks in which a central web is transversely placed and the ends of the block or brick have open ends with depending portions forming increased abutting surfaces at the ends, and having interlocking cavities and projections at the base to join the blocks together longitudinally, the panels or insets having transverse holes in which a tie bolt of rubber, or a metal bolt surrounded by a rubber tube or washer may be used.

Figure 5 is a plan in which the blocks or

bricks are arranged with their length in line with that of the gutter and kerb.

Figure 6 is a side elevation of brick or block having interlocking upper and lower ends and corners and projecting rib or member to fit into an indent of the base road surface.

Figure 7 is a perspective view of cavity and projecting lip block.

- 10 In carrying the invention into effect *a* is a block or brick of suitable rubber having a non-slipping hard wearing surface for the traffic obtained by vulcanizing or other suitable means. The block or brick *a* is formed 15 in moulding with a cavity *b*, having taper, rounded or other appropriate ends *c* to provide additional rubber substance *c¹* at the ends and give greater resistance to deflection by the traffic. Within the said cavities are 20 formed, inserted, moulded or placed insets or panels, cores or the like *d* made of cement, concrete, wood, asphalt or other suitable substance to form a reinforcement for the rubber surrounds to maintain a substantially 25 rigid or slightly yielding action to the pressure taking up parts during traffic moving thereon. The members *d* may be interlocked with the members *a* as shown at *e*, in Figure 3.
- 30 The upper sides of the members *a* may be extended as at *g*, Figure 4 to form a dovetail joint with a corresponding member *d* and so obtain increased resistance or strength where it is mostly required.
- 35 An interlock *h* for the members *a* may consist of a cavity at one end and a projection at the other end, so as to connect with each other or one kind of block or brick may have cavities and another projections at both 40 ends.

The kind of rubber employed for the wearing surface is that capable of offering a maximum resistance to wear and tear, and to the formation of a slippery surface, and may be 45 of the rough vulcanized rubber type.

j is the transverse hole and *j¹* the rubber tube or washer upon a tie rod or bolt of rubber to interlock the members *a*.

d¹ is the central web arranged transversely 50 to the member *a*. *m* indicates guttering and *n* kerbing composed likewise of rubber blocks or bricks.

The blocks or bricks designed to meet the 55 sides of the guttering or kerbing are provided with a prepared surface or layer of pliable or plastic material formed integrally with the block or brick when moulding, or separately formed or applied.

The rubber most suitable is that capable 60 of resisting hard compression and quickly restoring itself when the pressure is removed.

To further increase the paving efficiency, 65 slabs or layers of rubber in sheet form may be laid upon the concrete or other base and

the improved blocks laid upon them, either with or without the lower layer of rubber forming the base of the block or brick.

The blocks or bricks may have projecting 70 end pieces adapted to engage in recessed portions upon the next abutting block or brick, and these may be cemented or otherwise secured in position, the object being to avoid clearance between abutting members. To meet conditions where the traffic is not heavy 75 and it is otherwise desirable to have a reduced usage of rubber, the top, base and ends of the block or brick may be less substantial with an increased area or mass of panel, 80 inset core or the like.

A series block or brick in accordance with 85 this invention comprises the characteristic of a number of blocks or bricks embodied as one, the overall dimension of which will be equal to the length of a single block or brick multiplied by the number of single blocks or bricks to which it is desired to make the series block or brick equal, and these series blocks or bricks will have a curvature or deviation adapted to meet the 90 slope at each side and the crown of the road.

p is the projecting rib or member in Figure 6 and *r* the cavity and *h* the projecting lip in Figure 7.

By the term "rubber" is meant, rubber, 95 whether pure, reclaimed, composite, or any other substance of pliable nature which is suitable for the purpose.

Having now described my invention, what I claim as new and desire to secure by Letters Patent is:—

1. A block comprising a moulded shell of rubber material formed of upper, lower and end portions arranged integrally as one, a cavity in the shell between the said portions, 105 a core member of relatively harder material than rubber adapted to fill in the cavity, and thickened inner corners upon the shell shaped to give increased resistance to the disruptive effect, between the shell and core produced 110 by the traffic when the block is under traffic pressure.

2. A paving block comprising a moulded shell of rubber material, having upper, lower and end surfaces formed integrally as one, 115 a cavity in the shell formed between the said surfaces at the formation of the shell, and a filling of harder material to constitute a core member to fit the cavity which has thickened inner corners and to the shape of 120 which the ends of the core members are adapted to conform.

3. A block consisting of a moulded frame of rubber comprising upper and lower pliable surfaces, a cavity formed therebetween and divided by a central web and an inner block of material adapted to fill each side of 125 said cavity and form a reinforcement to prevent collapse of the said frame.

4. A moulded block comprising elastic 130

upper and lower layers, a plurality of cavities, a plurality of webs separating the cavities, and a plurality of reinforcements closing the cavities.

5 5. A moulded block comprising elastic upper and lower layers, projecting flanges and ledges thereon, a cavity between the said

layers, a relatively hard block closing the said cavity and a rib upon the lower layer to take into an indent on the road.

10

In testimony whereof I have signed my name to this specification.

JACK SHERIDAN COWPER
